UNITED STATES PATENT OFFICE

BORIS SILVERSTEIN, OF BROOKLYN, NEW YORK

WELTING OR GIMP

Application filed September 14, 1928. Serial No. 305,920.

This invention relates to welting or gimp used in connection with the joining of leather and similar materials.

In the manufacture of shoes, pocket books and similar articles of leather or artificial leathers it is ordinary practice to form a seam between two strips of the material by inserting what is generally known as a seam closing strip, which consists of a strip of material usually of leather, having a solid edge which is interposed between the two pieces of the material to be joined, the other edge thereof being made to coincide with the edges of the material. A row of stitching is then run through the three superimposed layers. It often happens in practice and particularly where cheap grades of leathers or leatherettes are being joined, that as the materials are folded and creased to flatten the seam, they crack during the flattening process or after short usage, thereby destroying the article with a consequent loss of both labor and materials.

With the foregoing in mind, it is the purpose of the present invention to provide a strip of welting of this character which may be used to join two pieces of material without requiring a fold to be made in the latter. I accomplish this purpose by means of a welting strip of the character hereinafter described, set forth in the appended claim and illustratively exemplified in the accompanying drawings in which: Figure 1 is a plan view of a strip of my improved welting; Figure 2 is a transverse sectional view taken on the lines 2—2 of Figure 1; Figure 3 is a plan view of two pieces of material joined by means of my improved welting strip; and Figure 4 is a transverse sectional view taken on lines 4—4 of Figure 3.

Figure 5 is a transverse sectional view of a slightly modified construction; and Figure 6 is a similar sectional view of a still further modification.

Referring to the drawings, and particularly to Figures 1 and 2, 10 denotes a strip of tape, preferably leather or suitably treated fabric, and 11 designates a strip of filler, usually cotton cord, which is placed upon the tape longitudinally thereof and closer to one edge

than to the other. The shorter side of the tape is then folded over on itself to a line short of the cord 11 and fixed by means of some suitable adhesive. The other side of the tape 10 is also folded upon itself to overlie the cord 11 and to meet or project very slightly over the edge of the shorter side, as shown in Figure 2. Adhesive is used to fix this side also. The welting strip in its complete form is ready to be used in seaming a great variety of materials and is made up in long strips.

Referring now to Figures 3 and 4, I have shown one application of my improved welting in which the latter is placed between two pieces of material 12, the edges thereof being arranged adjacent opposite sides of the bulge made by the cord filling 11 and a row of stitches 13 run through each piece of material 12 and the underlying side of the welting. It will be clear that if the article is to be folded at the seam the welting will be the portion taking the fold instead of material of the article itself, the solid edge of the welting forming a beaded effect which may be further accented by utilizing a welt of contrasting color.

In Figure 5, I have shown the welting made up of two separate strips 10' of material disposed about the interposed filling or cord 11, the strips being brought together and held by an adhesive. In Figure 6, the welting is made from a single piece 10" of material which is folded on itself and the side edges brought together, the filling 11 being interposed between the folds and the material held together by an adhesive, as previously described.

Having now described my invention what I claim as new and desire to secure by Letters Patent is:

A welting strip, comprising a flat strip of material folded on itself with side edges overlapping, a filler strip disposed centrally and longitudinally between the layers of the folds of the strip, the sides of the folded material beyond the filler strip being flat to receive the edges of materials to be joined.

In testimony whereof he has affixed his signature.

BORIS SILVERSTEIN.
